FILING DEVICE

Filed April 15, 1944

UNITED STATES PATENT OFFICE

2,415,054

FILING DEVICE

Marcel Weil, New York, N. Y.

Application April 15, 1944, Serial No. 531,153

2 Claims. (Cl. 129—31)

1

This invention relates generally to filing devices and more particularly to devices, cases or boxes carrying index cards, papers, or any other substantially flat articles to be successively arranged and in stacked relation.

It is an object of this invention to provide follower means cooperable with one or more relatively narrow slots which extend into and lengthwise of the base plate of a filing device, thereby only inordinately affecting the article carrying surface of the base plate and practically keeping the latter smooth and uninterrupted.

It is a further object of this invention to provide follower means which is sturdy, simple and inexpensive in construction and includes as integral parts thereof a plurality of lug members cooperable with the base of the filing device which guides said follower lugs within small slots cut a predetermined distance and in angular relation to one another through the surface into the material of the base plate.

It is another object of the invention to provide follower means which is prevented from undesired disengagement, tilting or removal from the base plate of the filing device along which it is adapted to slide.

It is still a further object of this invention to provide means for manually releasing the follower when the same is to be moved or slid along the base plate and to brake said follower after it has assumed a desired position relatively to the base plate.

It is still another object of this invention to provide means for improving the follower for filing devices, for simplifying the latter and reducing the space for installing the same in the base plate.

These and other objects and advantages of the invention will appear from the following disclosure thereof together with the attached drawing which illustrates certain forms of embodiments thereof. These forms are shown for the purpose of illustrating the invention since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the drawing:

Fig. 1 shows in perspective a filing device (part thereof being broken away) embodying the invention.

Fig. 2 is a sectional view taken along line 2—2 of the device of Fig. 1.

Fig. 3 illustrates in perspective the follower employable in the filing device of Fig. 1.

Figs. 4, 5 and 6 are cross-sectional views of

2

filings devices embodying the invention in different modified forms.

Fig. 7 is a fragmentary and sectional view of the follower on somewhat enlarged scale and shown in the position for sliding along the base plate of the filing device.

Fig. 8 is a view similar to that of Fig. 7 with a stack of articles abutting against the follower which in turn assumes a braking position relatively to the base plate of the filing device.

Referring now in greater detail to the drawing, there is shown in Fig. 1 a box 10 for a filing device which has the end or front and rear walls 11 and 12, side walls 13 and 14 and bottom wall 15a which walls are secured to base plate 15 in any convenient manner, such as by glue, tacks and the like. While said walls 11, 12, 13, 14 and 15a may be made from cardboard or any other inexpensive material, base plate 15 is preferred to be manufactured from wood, strong paste board, plastic substance or composition adapted to be cut by means of a saw blade to provide therein oblique and oblong slots or grooves 16, 17.

Surface 18 of base plate 15, which is adapted to slidably receive and support index cards or any other flat articles in substantially upward position and in successive arrangement, is smooth and practically uninterrupted since the same carries slots 16 and 17, each of very narrow width.

Slots 16 and 17 are disposed in angular relation to each other, are arranged spaced apart from each other and extend from the surface 18 of base plate 15 into the center portion of the latter a predetermined depth 19 for a purpose about to be described.

A follower member 20 made from sheet metal or other bendable material, substantially rectangular in shape, is provided with a sliding portion 21 from the lateral ends of which extend downwardly and inwardly bent lugs 22, 23 which are disposed with respect to each other in substantially angular relation, as are the aforementioned slots 16 and 17 in base plate 15. The length of lugs 22 and 23 correspond approximately to the depth of slots 16, 17.

As is apparent from Figs. 2 and 3, upwardly extending plate 24 of follower 20 is inclined with respect to the base plate surface 18 and to flat sliding portion 21 which, in turn, bears on the center portion of said surface 18 to slide therealong and to guide lateral ends or lugs 22, 23 in lengthwise direction of slots or cuts 16 and 17. Lugs 22, 23 have substantially the same width as that of said flat part or portion 21.

It is well understood that in order to assemble the filing device, all that is to be done is to insert from one end of base plate 15 follower lugs 22, 23 in slots 16 and 17 and to then secure base plate 15 to bottom, side and end walls 15a, 13,

14 and 11, 12 of box 10. Base plate 15 corresponds to the length of bottom wall 15a and may also be of substantially the same width thereof.

Follower plate 24 may be of a width substantially corresponding to the width of box 10 but may preferably be shorter than the height of box 10. It is well apparent that due to this construction of the follower member with its lugs 22, 23 penetrating a sufficient distance (depth 19) into slots or cuts 16 and 17, the member is effectively prevented from tilting on base plate 15 in lateral direction or undesired removal from the base plate 15 in upward direction. However, the width of lugs 22, 23 permits the plate to be swung or tilted in endwise direction of base plate 15 as indicated in Fig. 8, thereby bringing about frictional engagement of lugs 22, 23 with the walls defining slots 16 and 17 in base plate 15 and with surface 18 of the latter. This position (Fig. 8) is normally assumed when a stack of articles 25, such as index cards, abuts against the upright plate 24. Upon swinging movement of plate 24 together with slide portion 21 and lugs 22, 23 in direction of arrow A and into position of Fig. 7, the slide 21 of follower 20 comes to lie flush with the surface 18, and follower 20 may then be displaced a desired distance for adjusting or similar purpose lengthwise of base plate 15 and along slots 16 and 17 thereof.

Figs. 4 to 6 illustrate various modified embodiments of the invention.

According to Fig. 4 the follower 40 is made substantially of the same material and has about the same shape as that shown in Fig. 3. However, slide with plate 41 is somewhat shorter than plate 24 and its lug 42 is bent outwardly and downwardly, whereas lug 43 is positioned at a lateral end of follower plate 41. This arrangement has the advantage that base plate 45 when inserted in filing box 44 may be made somewhat narrower than bottom wall 45a, thereby leaving a lateral guide slot or gap 47 into which lug 43 projects, while within the confines of the surface of the base plate 45 only a single groove or slot 46 may be provided which angularly extends with respect to slot 47, is deep enough and positioned at such location of the base plate so as to prevent any lifting or removal of follower 40 from the base plate 45 when the latter is secured within box 44.

As seen in Figs. 4 to 6 the follower plate is shorter than the width between the side walls of the filing device. It is well apparent that this follower plate may also be made to be guided along the inner face of said side walls, if so desired.

Fig. 5 shows follower 50 within box 54 and provided with lugs 52, 53 depending from the ends of the sliding portion of follower plate 51 and arranged in angular relation to one another.

Fig. 6 indicates a follower 60 whose plate 61 has lateral and inwardly bent end lugs 62, 63 adapted to engage horizontal slots 66 and 67 accommodated in base plate 65 which, in turn, is secured to the bottom wall of box 64. As can be realized from Fig. 6, lugs 62, 63 are substantially U-shaped and thus prevented from disengagement with base plate 65 when the latter is inserted in box 64.

Only upon movement of follower 60 to the forward or rearward end of base plate 65, removal of follower 60 from said base plate 65 may be

had. Otherwise, operation and result contemplated by this invention are substantially the same with respect to the other filing devices shown.

5 It is well understood that the base plate or support herein referred to may form the bottom plate proper of the filing device 10, and further such plate is not necessarily to be positioned on the bottom of device 10, but may be disposed at or form one of the side walls of said filing device. The width and length of the lugs and the direction in which they extend may be, of course, varied, keeping, however, always in mind that the follower should be thereby impeded from disengagement or removal from the support or plate with which the lugs engage.

As many possible embodiments may be made of the above invention, and as many changes might be made in the embodiments above set forth, it is to be understood that all matters hereinbefore disclosed or shown in the accompanying drawings are to be interpreted as illustrative and not in a limiting sense.

Having thus described the invention what is claimed as new and desired to be secured by Letters Patent, is:

1. A filing device comprising an elongated base plate having a center portion, a follower provided with an upright plate, a slide connected to and forming an angle with said upright plate, said center portion of said base plate being provided with a pair of spaced cuts forming an angle with each other and converging toward each other, said cuts extending lengthwise of and into the surface of said base plate, said slide being provided with a substantially flat part for contact with the surface of said base plate and terminating into downwardly bent lateral ends having substantially the same width as that of said flat part, said lateral ends forming lugs, said lugs slanting toward each other and engaging said converging cuts, whereby said follower may be displaced by moving said flat part of said slide along the surface of said base plate, while said lugs are prevented from disengagement with said cuts in the direction of said upright plate.

2. A filing device comprising an elongated base plate having a center portion, a follower provided with an upright plate having a width substantially corresponding to the width of said base plate, a slide connected to and forming an angle with said upright plate, said center portion of said base plate being provided with a pair of spaced cuts forming an angle with each other and converging toward each other, said cuts extending lengthwise of and into the surface of said base plate, said slide being provided with a substantially flat part for contact with the surface of said base plate and terminating into downwardly bent lateral ends having substantially the same width as that of said flat part, said lateral ends forming lugs each extending in an angle with respect to said flat part, said lugs slanting toward each other and engaging said converging cuts, the length of said lugs corresponding substantially to the depth of said cuts, whereby said follower may be displaced by moving said flat part of said slide along the surface of said base plate, while said lugs are prevented from disengagement with said cuts in the direction of said upright plate.

MARCEL WEIL.
